UNITED STATES PATENT OFFICE

CHARLES S. WARNOCK, OF LOS ANGELES, CALIFORNIA

DESIGN FOR A VENTILATOR FOR VEHICLES

Application filed July 29, 1930. Serial No. 36,511. Term of patent 14 years.

To all whom it may concern:

Be it known that I, CHARLES S. WARNOCK, a citizen of the United States, and a resident of Los Angeles, Los Angeles County, California, have invented a new, original, and ornamental Design for Ventilators for Vehicles, of which the following is a specification, reference being had to the accompanying drawings, forming a part thereof.

Figure 1 is a perspective view of a ventilator for vehicles, showing my new design.

Figure 2 is a perspective view of the same from the opposite side.

I claim:

The ornamental design for a ventilator for vehicles, substantially as shown.

CHARLES S. WARNOCK.
